WASHING MACHINE MECHANISM

David Hays, Fairfield, Conn., assignor to General
Electric Company, a corporation of New York

Application May 27, 1936, Serial No. 82,033

1 Claim. (Cl. 68—131)

The present invention relates to washing machines of the type having an agitator which is moved orbitally in order to effect the washing action.

5 The object of my invention is to provide an improved construction and arrangement in washing machines of this type and, for a consideration of what I believe to be novel and my invention, attention is directed to the accompanying 10 description and the claims appended thereto.

In the accompanying drawing, Fig. 1 is a sectional elevation of a washing machine embodying my invention, and Fig. 2 is a top plan view of the washing machine shown in Fig. 1, partly 15 in section and partly broken away.

Referring to the drawing, the tub 1 is supported at its outer edge by a cylindrical skirt 2 to which are affixed supporting legs 3. A rubber bead 4 which is mounted on the upper edge of 20 the skirt 2 provides a cushion support for the tub. A gear casing 5 extends diametrically across and is bolted at either end to the depending sides of the skirt 2. Integral with the upper side of the gear casing is a cylindrical post 6 which extends through a central opening in the bottom 25 of the tub. The post is provided with a flange 7 which supports the tub. The opening in the bottom of the tub is sealed by a flexible diaphragm 8, of rubber or other suitable material, the edges 30 of which are clamped to the bottom of the tub by screws 9 which are threaded through a clamping ring 10 into the flange 7. A suitable gasket 11 is provided between the flange 7 and the bottom of the tub in order to prevent leakage. 35 When the screws 9 are threaded in place the tub is wedged tightly against the rubber bead 4, thereby providing a solid mounting for the tub.

The diaphragm 8 has hollow cone or dome-shaped portion 12 which flares inwardly and upwardly toward the center of the tub. On the upper end of the dome-shaped portion 12 is positioned an agitator 13. This agitator may be of any suitable shape and, for purpose of illustration, is shown as a corrugated disk. The agitator is driven by a shaft 14 which extends upwardly from the gear casing through the dome-shaped portion 12 of the diaphragm, and which is connected to the agitator by a screw 15. The agitator and the shaft 14 are respectively provided with spherical shaped metal plates 16 and 17 which conform to the surface of the diaphragm and provide extended clamping surfaces for securing the shaft and the agitator to the diaphragm. The plates 16 and 17 prevent any leakage around the screw 15 and also distribute

the stress on the diaphragm. At the lower end the shaft 14 is provided with a ball 18 which is rotatably held in a socket in the outer end of a crank 19. The crank is carried by a vertical shaft 20 and, since the shaft 14 is inclined inwardly from its lower end toward the vertical, rotation or oscillation of the crank 19 will cause the axis of the agitator to be moved orbitally about the shaft 20. Due to the ball and socket connection between the shaft and the crank the shaft is not rotated by the crank. During the orbital movement of the agitator successive portions of the agitator will be depressed and subsequently elevated, and this movement of the agitator produces a rubbing and stirring action on the clothes which effects the washing. During washing the dome-shaped portion 12 of the diaphragm is subjected to a continual flexing, assuming the instantaneous shape generally indicated in the drawing. The flexing of the diaphragm is dependent somewhat on the resistance encountered by the agitator and, while the agitator is normally held in a central position, the flexibility of the diaphragm is sufficient to permit lateral movement of the agitator if the agitator encounters sufficient resistance such as may result from unbalanced distribution of the clothes. This lateral movement eliminates any danger of damaging the clothes. The dome-shaped portion 12 of the diaphragm has the further function of preventing tangling of the clothes at the center of the tub since the clothes tend to slide over the flaring sides of the diaphragm toward the outside of the tub. Tangling of the clothes at the center of the tub is further prevented by oscillating the crank 19 instead of rotating it continuously in one direction.

For oscillating the crank 19 I have used the driving mechanism illustrated in application Serial No. 65,597, filed February 25, 1936. In accordance with this construction the vertical shaft 20 is suitably journaled in a boss 21 in the gear casing, and on the lower end of the shaft 20 is fixed a pinion 22 which meshes with a reciprocating rack 23. The left end of the rack is provided with a crank pin 24 which is rotatable in a bearing eccentrically located in a worm wheel 25. The worm wheel is keyed to the lower end of a vertical wringer drive-shaft 26 which is journaled in a bearing 27 in a tubular wringer post 28. The wringer post is clamped to the upper wall of the gear casing by a split clamp 29 integral with the upper wall of the gear casing. The worm wheel is rotated by a worm 30 which is driven by an

electric motor 31 carried on the gear casing by rubber rings 32 clamped to supports 33. An intermediate shaft 34 is connected between the motor shaft 35 and the worm shaft 36 by flexible 5 couplings 37. A thrust ball 38 is provided at the end of the worm shaft which is adjusted by means of a screw plug 39. With this arrangement the worm wheel 25 is continuously rotated in one direction by the motor, and the crank pin 24 bearing in the worm wheel causes the rack 23 to be reciprocated. The angle of oscillation of the crank may vary from a fraction of a revolution to one or more complete revolutions depending upon the size of the pinion 22 and the travel of the rack. 10 15 The reciprocating movement of the rack is guided by a guide 40 having rearwardly extending ears 41 pivoted on a plunger 42. The plunger 42 is slideable in the side wall of the gear casing and is biased outwardly to a position in which the rack is 20 out of mesh with the pinion 22 by a coil spring 43. The plunger is moved inward to the position shown in Fig. 2 by a cam 44 on a control lever 45 which is pivoted on a bracket 46. The inward movement of the plunger is adjusted by means of 25 a set screw 47 which is threaded on the end of the plunger.

On the underside of the crank pin 24 is a friction pin 48 which is urged by spring 49 against the gear case cover 50. The friction pin 48 holds the 30 crank pin 24 in its bearing in the gear wheel 25; supports the wringer shaft 26, and thereby prevents vertical movement of the wringer shaft which would change the mesh between the worm wheel 25 and the worm 30; and also offers frictional resistance to the reciprocating movement of 35

the rack, which tends to prevent overtravel of the rack.

In the use of the washing machine the tub is filled with liquid to a level somewhat higher than the highest position of the agitator and the 5 clothes to be washed are loaded in the tub. The control lever 45 is then moved to the position shown in Fig. 2, thereby moving the rack into engagement with the pinion 22 and starting the oscillation of the crank 19. During the oscillation of the crank, the axis of the agitator is moved orbitally about the shaft 20. The agitator has a wobbling movement in which successive portions of the agitator are depressed and subsequently elevated. This produces a stirring and rubbing 10 15 20 25 30 35 action which effects the washing. At the conclusion of the washing operation the control lever 45 is moved to the position in which the rack is out of mesh with the pinion 22, thereby stopping the washing action.

What I claim as new and desire to secure by Letters Patent of the United States, is:

In a washing machine having a tub provided with an opening, a flexible diaphragm for sealing said opening, an agitator in the tub above the 25 diaphragm, means including said flexible dia- phragm for resiliently centering the agitator, a driving member for the agitator extending through the diaphragm and fixed thereto in sealing relation, and means on the side of the dia- phragm opposite the agitator for moving the driv- ing member orbitally without rotating it substan- tially.

DAVID HAYS. 35
